Design for the handle of a

Patented Sept 13 1859

Henry Rockhardt
Design for the handle of a
Patented Sept 13 1859

Des. 1145

Henry Hebbard, of New York, N. Y.
Letters Patent No. 1145, Dated Sept 13, 1857.

The schedule referred to in these Letters Patent and making part of the same.

To all whom it may concern:

Be it known that I, Henry Hebbard, of the City, County, and State of New York, have invented a new and original device for ornamenting the handles of spoons, forks, and other articles of table cutlery whether made of silver or other metal, and I do hereby declare the following to be a full description of the same reference being had to the accompanying drawings forming a part of this Specification, the same letters of reference referring to like parts, wherever they occur.

Figure 1. is the front side of the Spoon.

2. the back side of the Spoon.

Letter a, is the front shield, at the head of which is a five-pointed shell like ornament b, and around the shield, and between an outer and inner raised marginal threads c. c. is a bead like bordering d, to give to the shield a brooch like appearance.

At the point of connection between the stem e. of the spoon, and the shield, is a thistle leaf like device f, composed of four leaves of a triangular form, the apex of which rests upon a dash like device g, extending down the stem e, supported on each side by raised threads; and branching from the crown of the device are two horn like devices h, which over lap the bordering surrounding the shield at its juncture with the stem.

The face of the stem is concave, and has at its outer edge a raised thread i. At its juncture with the bowl j, is a six-pointed leaf k, upon the stem l, which is a heart l, which supports a dash like device m, extending up the stem e, to complete the device on the front side of the spoon.

Letter a², is the reverse side of the shield, having around its margin the same ornamentation as described on the front side.

At its juncture with the stem is a leaf like device composed of three acorn leaves, m, so arranged by overlaying as to form a broad leaf like ornament, held together by their stems p, twining around the bordering of the shield.

From the point of the leaf m, extends down the stem a dash like device q, formed by the folding of an acorn leaf, so as to expose its edges at its point.

2

Des. 1145

of overlapping. Adown the sides of the stem, are two marginal raised threads r, which terminate at the shanks of the spoon in scroll like buttons. Branching up from between them is an acorn like leaf device t, composed of two side leaves, and a middle overlapping leaf, united together by their stems with a knot or bead u, from which extends up the stem of the spoon a dash like device v.

From underneath the point of the overlapping leaf t, is a dash like device w, composed of three stems which combine and terminate in a single point, near the tip of the bowl of the spoon, to complete the device for ornamenting the handles of spoons, forks, and other articles of table cutlery.

Having now described my invention I will proceed to set forth what I claim and desire to secure by letters patent of the United States.

What I claim is the use of the ornamental devices hereinbefore described, for the purpose of ornamenting the handles of spoons, forks, and other articles of table cutlery, whether made of silver or other metal.

Witnesses.

Charles L. Barratt.

Albert Smith.
